GAME

Filed Feb. 4, 1924

Inventor.
George Modjeska.
Atty.

UNITED STATES PATENT OFFICE.

GEORGE MODJESKA, OF PEORIA, ILLINOIS, ASSIGNOR OF ONE-HALF TO VICTOR H. GABLER, OF PEORIA, ILLINOIS.

GAME.

Application filed February 4, 1924. Serial No. 690,454.

To all whom it may concern:

Be it known that I, GEORGE MODJESKA, a citizen of the United States, and a resident of Peoria, in the county of Peoria and State of Illinois, have invented certain new and useful Improvements in Games, of which the following is a full, clear, and exact description, reference being had to the accompanying drawing, forming part of this specification.

My invention relates to cards with which special games may be played, which, have in addition to the fascination of playing a game, the further advantage of a certain educational value.

One object of my invention is to provide an interesting game which, for example, will teach the players the call letters, location, wave length and sending range of various radio broadcasting stations. It is of course apparent that other subjects may be treated by the same or similar method.

The accompanying drawing represents eight cards of a pack suitable for playing the game and of cards shown, the three appearing at the top of the sheet, in addition to showing the essential features of the game, show a further step in the educational as well as the advertising value of the game.

By referring to the drawing it is to be noted that each card carries an index on each corner and with particular reference to the first card it will be seen that this card carries index "A", is geographically designated as New York, carries the call letters WEAF, indicates that this radio station broadcasts on a wave length of 492 meters, and has a sending range of 1500 miles. Similarly each of the other cards shown has its index, radio station, location, wave length and sending range designated.

To refer to the advertising value of the game, it will be noted that the three cards forming the upper tier of those shown carries the representation of a loud speaker and in cases where the game is to be distributed by the manufacturer of some particular loud speaker or other radio apparatus, an illustration of that apparatus may appear on the face of the card as suggested.

The pack consists of fifty-one cards made up of seventeen groups of three cards each, which are triplicates, that is to say, there

will be three of the cards like the first one designated as "A-WEAF-New York", and similarly three of each of the others to complete the pack.

The procedure in playing the game is that after the cards are well shuffled, each player is dealt five cards, one at a time face down and the remainder of the pack placed in the center of the table. In playing the game as now described, the word "radio" forms a part of the play and if when he examines his cards one of the players finds that he has cards having index letters spelling the word "radio", that hand of the game is concluded and the player having these cards announces "radio" and lays his cards face up upon the table and counts ten points.

If no such announcement is made upon the completion of the deal, the player to the left of the dealer draws the top card from the remainder of the pack and after arranging his cards in a manner satisfactory to himself, discards a card face up adjacent to the remainder of the pack. If the result of this drawing is to complete the spelling of the word "radio" this player makes his announcement and scores his points.

If a player has or draws all of the three cards of one station, he plays them face up and scores four points. When a player has or draws two cards of any one station, he may play them face up and score one point.

After a player has drawn and discarded, the player next to his left, may either draw the discard, the value of which he knows, or he may draw one from the remainder of the pack, and the play continues until one of the players has played his five cards or until the pack is exhausted at which time the various scores are recorded for each player, and the cards re-shuffled and again dealt.

Twenty-five points is a game.

It will be seen from the above that a pack consists of sets of groups of cards, all of the cards of one group agreeing with the others and having the same index; that the play consists of either using the indices to form a predetermined combination, or playing the cards in groups or fractional groups.

It will also be seen that the play may consist in predetermining a total for the meters or wave length, or the miles of send-

ing range (in packs arranged as illustrated) and permitting a play when that total has been obtained.

It will also be seen that by arranging 5 illustrations of various apparatus on the cards, the feature of advertising can be given considerable prominence.

Having thus fully described my invention, I claim:

- 10 1. A card game comprising a plurality of groups of cards each group carrying the call letters of a radio broadcasting station and a letter index.
- 15 2. A card game comprising a plurality of groups of cards, each group carrying the call letters of a radio broadcasting station, the name of the city where such station is located, and a letter index.
3. A card game comprising a plurality of

cards each card carrying an identification 20 of a radio broadcasting station and an index.

4. A card game comprising a plurality of cards each card carrying the identification 25 of a radio broadcasting station, an index, and the wave length of that station.

5. A card game comprising a plurality of cards each carrying the identification of a radio broadcasting station, an index, the wave length of that station, and its sending 30 range.

6. A card game comprising a plurality of groups of cards each group carrying the identification of a radio broadcasting station, an index, the wave length of that station, and its sending range. 35

GEORGE MODJESKA.
